UNITED STATES PATENT OFFICE.

SIDNEY QUAYLE, OF HILLSBORO, TEXAS.

REMEDIAL APPLIANCE.

1,081,148.

Specification of Letters Patent.

Patented Dec. 9, 1913.

Application filed December 17, 1912. Serial No. 737,238.

To all whom it may concern:

Be it known that I, SIDNEY QUAYLE, a citizen of the United States, residing at Hillsboro, in the county of Hill and State 5 of Texas, have invented new and useful Improvements in Remedial Appliances, of which the following is a specification.

This invention relates to a remedial appliance, and its object is to provide a device in the form of a bracelet or anklet adapted to be worn upon the person of the wearer and to hold a medicament for absorption and distribution throughout the body, whereby efficient treatment may be accorded, such device being so constructed as to facilitate its application and removal and the application and removal of the medicament carrying means, and adjustable to vary its diameter within reasonable 20 limits.

The invention consists of the features of construction, combination and arrangement of parts hereinafter fully described and claimed, reference being had to the accompanying drawings, in which:—

Figure 1 is a perspective view of an electrotherapeutic bracelet or anklet embodying my invention. Fig. 2 is a central longitudinal section of the same. Fig. 3 is a 30 vertical transverse section.

The device comprises a bracelet, anklet or similar article composed of two approximately semi-circular tubular sections 1 and 2, each preferably having a semi-elliptical outer face 3 and a flattened inner face 4, the latter being adapted to lie in close contact with the body of the wearer when the device is applied for use.

The ends 5 and 6 and 7 and 8 of the sections 1 and 2 are arranged in proximate relation, and the said ends 5 and 6 are preferably closed, while the ends 7 and 8 are open and adapted to be closed by screw caps 9. Each section contains a body of 45 cotton or other suitable absorbent material 10, saturated with the medicament to be employed, which passes out into contact with the person of the wearer for absorption and distribution through perforations 50 11 in the inner flattened faces 4.

The ends 5 and 6 are coupled at their outer sides by interengaging members forming a hinged joint 12, adapting the anklet or bracelet to be opened and closed 55 for application to and removal from the part of the body on which it is intended to

be worn. A strip 13 is secured to the inner surface of one of the tubular sections adjacent to the hinged joint and overlaps the inner surface of the other tubular section so as to cover the joint and form a smooth interior for the closed anklet or bracelet and at the same time limit the hinging movement of the tubular sections on each other.

It will be understood, of course, that the absorbent medicament carrying bodies are insertible and removable through the ends 7 and 8 of the tubular sections when the caps 9 are detached. Secured at one end to the inner face of one of the sections, as the section 2, adjacent to its end 8, is a spring strip 14, which is adapted to bear upon and overlap the inner face of the end 7 of the other tubular section 1, and to close the 75 joint on the inner side of the anklet between the said ends 7 and 8 of said sections, and to provide a smooth inner contact surface at such point, as well as to serve as a guiding and fastening member in connecting 80 and disconnecting such ends of the sections. A fastening strip 15 is secured at one end to the outer face of the end 7 of the section 1 and overlaps the end 8 of the section 2, its 85 said overlapping end being provided with a longitudinal slot 16 engaging guide posts 17 on said section 2, which guide posts are provided with clamping nuts 18 or other suitable means for securing said strip in position, and thus fastening the device upon 90 the person of the wearer. It will thus be understood that the strip 15 forms a covering element to close the outer side of the joint between the ends 7 and 8, and co-operates with the strip 14 to form guides in 95 bringing the free ends of the sections 1 and 2 together, which construction renders the anklet or bracelet adjustable to vary its diameter within certain limits, for a purpose readily understood.

I claim:—

A remedial appliance comprising a hollow annular body formed of substantially counterpart sections, each of said sections being permanently closed at one end and 105 provided with a removable plug for closing the opposite end thereof, the closed ends of said sections being hingedly connected and the inner faces of the respective sections having perforations formed therein, a covering strip secured to the closed end of one 110 of the sections to extend across the joint and

overlap the closed end of the other section on the inner surface of the hollow body, a covering and guide strip upon the inner face of the open end of one of the sections adapted to bridge the intervening joint and overlap the open end of the other section, a fastening strip secured at one end to the outer surface of the closed end of one section and adapted to overlap the outer surface of the closed end of the other section, said strip having a longitudinal slot therein, threaded projections upon the closed end

of the latter named section adapted to project through said slot, nuts carried by said threaded projections to engage said slotted strip and adjustably fasten the sections together, and a body of absorbent medicament carrying material within each body section. 15

In testimony whereof I affix my signature in presence of two witnesses.

SIDNEY QUAYLE.
